LIQUID CONTROL FOR STORAGE TANKS

John J. McGillis and Hugh D. McGillis,
Brockton, Mass.

Application May 4, 1945, Serial No. 591,968

4 Claims. (Cl. 137—68)

1

This invention relates to improvements in liquid control mechanism for storage tanks and the like and more particularly to improved means for modifying the effects of inflowing liquid, thereby to prolong the useful life of such tanks and for ensuring against an overflowing amount of oil or other liquid being delivered into a tank.

The invention is herein disclosed in its application to domestic fuel oil storage tanks, although it will be understood that our improved mechanism may be employed with advantage in connection with any container which is required to hold relatively large quantities of liquid which is to be drawn off and replenished from time to time.

Storage tanks, and more especially oil storage tanks, ordinarily have an inlet opening in a top wall thereof through which oil may be delivered into a tank. If a tank is filled or replenished by gravity inflow of oil through the top opening, the incoming stream of oil customarily is directed downward with considerable force against the bottom wall opposite the top opening, and we have found that a large percentage of such tanks which fail because of deterioration, fail at this region of bottom wall against which the forcible streams of incoming oil are directed. Although sediment may collect to a considerable thickness on the bottom of such tanks over a period of use, the layer of sediment has little effect as a protection for the bottom wall because the force of an incoming stream of oil riles and displaces any sediment against which it strikes, and substantially the full force of the stream is taken by a relatively small area of tank wall. Also, as will be obvious, the riling of the sediment with consequent dissemination of solid particles through the oil in the tank, promotes clogging of fuel lines and filters to an extent which frequently causes annoyance and often results in discomfort and substantial expense to oil consumers.

Furthermore, the current practice of speeding oil deliveries by forcibly pumping the oil from delivery trucks into consumer storage tanks has greatly aggravated the mentioned conditions both as to the deteriorating effects of the oil streams on tank walls and as to riling of sediment.

Also it not infrequently happens that fuel oil tanks overflow onto the floor when their supply is being replenished, due to lack of suitable means to prevent such overflow. Visual gages are subject to sticking and being inaccurate, and the truck driver may be otherwise engaged and not

2

notice that a tank is full or overflowing, until considerable oil has spilled on the floor to become a hazard if ignited, and disagreeable in any event.

It is among the objects of our invention to provide means within oil storage tanks and the like for distributing an incoming stream of liquid so that no substantial impact or pressure is directed against any limited area of wall within the tank. We provide for reducing the incoming stream to a spray so that the liquid falls gently over a large area, with no appreciable disturbance of sediment which may have accumulated at the bottom of the tank.

Another object is to provide means, in conjunction with our said spray means, for positively stopping inflow to the tank when the liquid therein has risen to a predetermined maximum level. We provide within our spray nozzle a valve control which may be manually set in open position

for free inflow of liquid and which automatically closes in response to a predetermined rise of a float.

It is, moreover, our purpose and object generally to improve upon prior storage tank controls.

In the accompanying drawings:

Figure 1 is a more or less diagrammatic view in vertical cross-section, through a building wall and a fuel oil storage tank, the tank having an embodiment of our invention associated therewith;

Figure 2 is a vertical cross-sectional view through the spray nozzle, on a larger scale, and showing the valve and its control mechanism;

Figure 3 is an elevational view looking from the left in Figure 2; and

Figure 4 is a perspective of our float-actuated valve latch.

Referring to the drawings, and more particularly to Fig. 1 thereof, a domestic fuel oil storage tank 10 is shown supported by the legs 12 at a suitable elevation above a cellar floor, or the like, 14. The tank is shown located adjacent an outside wall 16 of a building, and the usual vent pipe

18 is represented extending from the tank through the wall 16 and provided exteriorly with the usual vent cap 20.

A usual fill pipe 22 also extends through the wall 16, it having a drop-cover receiving end 24 exposed exteriorly of wall 16 and extending thence through the wall to a mid-location above the top wall of tank 10 where it is connected to the unit, indicated generally at 26, which embodies our present invention and which is shown

mounted in the inlet opening 28 in the top wall of the tank.

Referring now to Figs. 2-4, the unit 16 comprises a tubular housing which conveniently may be made in three parts as represented, the upper part 30 being a tubular elbow with one outlet connected to the fill pipe 22 and the other connected to a valve housing 32, flanged at its lower end at 34, so that it may be bolted to the usual flanged element 36 which is screwed into the top opening 20 of the tank.

The third part 38 of unit 26 is a tubular nozzle whose upper end is shown threaded into valve housing 32 and which depends from said housing through the element 36 to an appreciable distance down within the tank where its lower end is capped as at 40.

The side walls of the tubular nozzle 38 have the multiple slots 42 therein distributed along the vertical extent of the nozzle so that liquid entering the nozzle cannot escape excepting through the slots, thereby to produce a lateral spray all along the nozzle and at least at two opposite sides thereof. As shown, the slots are in only two opposite side walls which preferably will be disposed so that their sprays will be directed generally longitudinally of the tank. However, the slots may be otherwise arranged and, if desired, may have a staggered relation providing spray slots all around the nozzle tube.

A valve 44 is carried on the valve stem 46 which extends axially of the nozzle and out through the bottom cap 40, and a spring 48, coiled around the valve stem, yieldably urges valve 44 to its seat 50 in valve housing 32. However, a projection 52 on the lower end portion of the valve stem is adapted to be latched, as in Fig. 2, by the spring latch 54, at the lower end of the nozzle, thereby to hold the valve depressed away from its seat 50, against the tension of spring 48. Hence, with the valve latched open as in Fig. 2, oil or other liquid can pass freely from the fill pipe 22 into the interior of nozzle 38 for discharge as is pray into tank 10 through the slots 42.

Spring latch 54 has a depending leg 56 thereon which is pivotally mounted at 58 the relatively long lever 60 which has the float member 62 at the free end of its long arm. A lug 64 projects from the leg 56 and is inclined as best seen in Fig. 4 for limiting downward swing of float lever 60. Also the lug limits upward swing of the float lever about pivot 58. However, when the float has been elevated to bring the short arm of lever 60 against stop lug 64, a further upward movement of the float draws the spring latch 54 out of latching engagement with projection 52 on the valve stem, thereby permitting spring 48 to snap valve 44 to its seat 50, for cutting off flow into nozzle 38.

According to the invention, the valve 44 will be manually set in latched-open position prior to a loading of the tank. For this purpose, the valve stem 46 has the extension 47 on the upper side of the valve, and the extension projects into elbow 30 with a suitable guide strap or spider 66 internally of the elbow for maintaining the extension and also the valve stem and valve in correct axially disposed relation within the nozzle and elbow. A plunger 68 normally is in alignment with the extension 47, it having extent through a suitable packing nut 70 in the upper wall of elbow 30, with its upper end pivotally connected at 72 to the slotted arm 74 of a lever indicated generally at 76. This lever is pivotally mounted on the elbow as by being pivoted at 78 on the upstanding

bracket 80. As represented, the slotted arm 74 of lever 76 is the shorter of two arms whose longer one carries a weight W which constantly urges the lever clockwise about its pivot 78 thereby to maintain the plunger 68 in its elevated position of Fig. 2. The weighted arm of lever 76 has a chain or cable 82 connected to it and trained thence over a pulley 84 which may be mounted on any convenient fixed support such as the cellar ceiling 86. The chain or cable, after passing over the pulley, extends toward the building wall 16 and has connection to the inner end of an actuating rod 88 which extends slidably through wall 16, with a knob or handle 90 on its exterior end. The inner end of the rod 88 has a stop element 91 thereon for limiting outward movement of the rod.

The weighted lever 76 normally holds the plunger 68 elevated and the chain or cable 82 taut, with rod 88 in its innermost position of Fig. 2.

Assuming that valve 44 has been closed to its seat 50 and that it is desired to set it in latched-open position, as for filling tank 10, the extension 47 of valve stem would be in its dotted elevated position of Fig. 2. Hence by merely grasping handle 90 and pulling rod 88 outward, the plunger 68 will be driven downward against the upper end of extension 47 thereby depressing it and the valve and valve stem until the latter's projection 52 engages under the spring latch 54 which holds the valve open after handle 90 is released and weight W returns the plunger to its elevated position of Fig. 2. Preferably the upper end of valve stem extension 47 is provided with the head 92, and the lower end of the plunger 68 has a similar head 94.

With valve 44 latched open as in Fig. 2, the mechanism is in condition for loading of the tank, as by the insertion of the delivery truck hose nozzle in the exterior end of the fill pipe 22, and opening of the control valve by the truck man. Incoming oil enters the tubular nozzle 38 and discharges therefrom into the tank 10 as a distributed spray which deposits oil gently throughout a large interior area of the tank with no appreciable riling of sediment in the tank. As the level in the tank rises, the float is elevated and, at a predetermined maximum level, the float lever engages lug 64, and a slight further rise of the float flexes the spring latch 54 to the right in Fig. 2, thereby to release the valve stem for spring closure of valve 44.

Closing of valve 44 builds up pressure in the fill pipe 22 and the truck hose back to a cut-off valve at the truck.

After the supply from the truck has been cut off, either automatically or manually, the hose and fill pipe 22 will continue full of oil and this must be flowed into the tank 10 before the hose connection is broken. Again the handle 90 is grasped and pulled out to depress plunger 68 to unseat valve 44 long enough to drain the fill pipe and hose. However, the valve will not become latched open at this time because the latch 54 will be in its release position due to the elevated position of the float.

As soon as the fill pipe and hose have drained into tank 10, the hose connection may be broken with assurance that oil will not be spilled on the lawn or elsewhere on the consumer's premises.

If desired, an abutment 96 may be provided on cap 40 of the nozzle for restraining any tendency of spring latch 54 to bow toward the abutment

under the shock of projection 52 being sprung-urged against the latch.

We claim as our invention:

1. In a storage tank having an opening in an upper wall thereof and a fill pipe for conducting liquid to said opening, the combination therewith of means disposed interiorly of the tank at an upper region therein for receiving liquid delivered to the tank through said fill pipe and upper wall opening, said means comprising a tubular nozzle having a series of radial orifices in its walls for spraying liquid from said nozzle, a valve controlling flow to said nozzle and having a valve stem extending axially of said nozzle and projected out through an end wall thereof, a spring engaged around said valve stem within the nozzle and constantly urging the valve to closed position, means for releasably engaging said projected part of the valve stem for latching the valve in open position, manual means exteriorly of the tank for opening the valve, and means interiorly of the tank and responsive to change of liquid level therein for releasing the said latching means for spring-closing of the valve.

2. In a storage tank having an opening in an upper wall thereof and a fill pipe for conducting liquid to said opening, the combination therewith of means disposed interiorly of the tank at an upper region therein for receiving liquid delivered to the tank through said fill pipe and upper wall opening, said means comprising a tubular nozzle having a series of radial orifices in its walls for spraying liquid from said nozzle, a valve controlling flow to said nozzle and having a valve stem extending axially of said nozzle and projected out through an end wall thereof, a spring engaged around said valve stem within the nozzle and constantly urging the valve to closed position, means for releasably engaging said projected part of the valve stem for latching the valve in open position, a plunger extending to a location exteriorly of said tank, means biasing said plunger to an inoperative position, and manual means for actuating the plunger against its said bias to effect an opening of said valve.

3. In an oil storage tank having length substantially greater than its width and having a fill opening in the top wall of the tank, a spray nozzle mounted in said fill opening and projecting downward a substantial distance within the tank, said nozzle having generally cylindrical side walls defining a chamber whose lower end is closed, and said side walls of the nozzle having spray openings therein disposed in vertical rows and positioned for discharge of liquid only in directions generally lengthwise of the tank and free of any forcible impingement on walls of the tank, the portions of said nozzle walls standing opposite the side walls of the tank being free of spray openings.
4. In an oil storage tank having a fill opening in the top wall thereof, a spray nozzle mounted in said fill opening and projecting downward a substantial distance within the tank, said nozzle having generally cylindrical side walls defining a chamber whose lower end is closed, and said side walls of the nozzle having vertical rows of transversely disposed thin slots for discharging generally horizontally directed sheet-form sprays of liquid at vertically spaced locations in each vertical row of slots, and means for stopping discharge from the slots in response to a predetermined rise of the liquid level in said tank.
